UNITED STATES PATENT OFFICE.

NICOLAS EMILIE METHLIN, OF PARIS, FRANCE, ASSIGNOR TO SCHNEIDER & CIE.,
OF PARIS, FRANCE, A LIMITED JOINT STOCK COMPANY OF FRANCE.

QUICK-FIRING GUN.

Application filed January 3, 1925. Serial No. 429.

To all whom it may concern:

Be it known that I, NICOLAS EMILIE METHLIN, a citizen of the Republic of France, resident of Paris, France, have invented new and useful Improvements in or 5
Relating to Quick-Firing Guns, which is fully set forth in the following specification.

This invention relates to a device more 10 particularly applicable to small calibre guns recoiling on a cradle, and which ensures the cooling and provides for the expansion of the barrels.

Various forms of construction of the in- 15 vention are illustrated by way of example in the accompanying drawings in which:—

Figure 1 is a sectional plan of a part of a gun constructed according to the invention, the section being taken along the line 1—1 in 20 Figure 2, which is a cross-section along the line 2—2 in Figure 1. Figure 3 is a cross-section along the axis of the trunnions of the cradle, and along the line 3—3 in Figure 1.

Figures 4 to 9 illustrate another embodiment of the invention applied to conjugated guns which are so mounted that the energy of recoil of one of the gun barrels is utilized to assist the running out of the other, and vice versa; Figure 4 being a top plan view partly in section; Figure 5 is a sectional elevation taken on the line 5—5 of Figure 4; Figure 6 is a longitudinal sectional elevation along the line 6—6 of Figure 5; Figure 7 is a sectional elevation taken on the line 7—7 of Figure 5; Figure 8 is an analogous sectional view showing the members in another working position; and Figure 9 is an enlarged sectional detail view of a portion of the 40 device illustrated in Figure 5.

Referring to Figures 1 to 3 inclusive, A is the barrel in which the bore of the gun is directly made. This barrel carries, to guide it in the cradle B, a sleeve C, for example 45 screwed on to it at c, as is shown in Figure 1, and enclosing without clearance longitudinal ribs A¹, forming projections upon the front parts of the barrel. In practice, the said ribs will be preferably formed on 50 a hoop a, which may be made of a metal which is a better conductor of heat than steel, for example aluminium or an aluminium alloy.

The sleeve C is externally provided with 55 vertically projecting ribs C¹, which are

guided with practically no lateral or horizontal clearance, but with a certain amount of vertical clearance y in corresponding grooves b in the cradle B, and with horizontally projecting ribs C² guided in the grooves 60 b¹ in the cradle without vertical clearance, but with a suitable amount of horizontal clearance.

The chambers formed between the consecutive ribs A¹ and the wall of the covering sleeve C are put into communication with each other by the orifices a¹ pierced in the ribs; this allows the air or cooling fluid to circulate throughout all the chambers. This air or cooling fluid is forced through the 65 pipe D leading in at a point in the back part of the cradle B, and the mouth d of which is always in communication with the inside of one of these chambers, for which purpose ports c¹ are provided in the covering 70 sleeve.

Owing to this cooling, combined with the expansion of the gun communicated to a covering sleeve rationally guided, a perfect 75 guidance is permanently ensured, any play 80 in a vertical direction and in a horizontal direction being practically suppressed and only taking place between the guiding ribs in a radial as at z. In all these cases, any lifting or dropping of the barrel is prevented by the ribs C₂, while the ribs C¹ prevent any transverse displacement.

Referring to Figures 4 to 9 which illustrate an example of the application of the invention to a group of conjugated guns 90 where the energy of the recoil of one of the gun barrels is utilized to assist the running out of the other, and vice versa, the alternating movements in opposite directions of the two barrels, during recoil and running out, 95 or the return to battery, are made use of to control continuously a rotary member which transmits its movement to the common shaft of two fans which deliver the cooling fluid.

As in the preceding example, each of the barrels A is provided on its front part with a hoop a, having radial ribs A¹ pierced by orifices a¹ and over which is fitted without clearance a covering sleeve C provided with vertical guiding ribs C¹, and horizontal 100 guiding ribs C², sliding in corresponding grooves in the cradle B. Above each gun is installed a fan E for forcing air or a cooling fluid through the ports c¹ in the corresponding covering sleeve. The fans E are 110

keyed to a common shaft F provided with a driving member such as worm wheel G. This wheel G is driven by a worm H keyed to a shaft I the axis of which is parallel to the axes of the conjugated guns and which turns in bearings B¹, B² formed on the cradle B which is common to the two guns. During firing a movement of rotation is imparted to the shaft I. For this purpose, two helicoidal grooves I¹, I² are cut in this shaft extending helicoidally from each other. In one of the grooves I¹ engages a tenon j projecting radially inside a ring J sleeved upon the said shaft I, and which may also turn, 10 without longitudinal displacement, in a sleeve C³ attached to the covering tube C. A groove k is formed, along a generating line, upon a shaft K turning in bearings provided on the cradle B, and the axis of which is parallel to that of the shaft I and arranged in the same vertical plane as this axis. In this groove is guided, by a cotter, a bent lever L—M the end of one of the branches L of which can press against an inclined plane B³ provided on the cradle B. The arm M of the lever engages by means of its knob shaped end m, in a sliding bar N movable radially with regard to the shaft I in a guideway in the covering tube C. According to the position which each of the two bent levers L—M occupies during the operation, the sliding bar N enters or escapes from a notch j¹ provided in the corresponding ring J.

When one of the guns, for example the one on the left (Fig. 5) recoils, the corresponding ring J, prevented from turning by the sliding bar N, compels the shaft I by means of its catch j to rotate.

During this time, the end of the arm L of the bent lever corresponding to the other gun arrives upon the rear inclined plane B³ (Fig. 7), so that the corresponding sliding bar N is disengaged from the notch j¹, which enables the corresponding ring J to turn with the shaft I. But as soon as the lever L—M of the left hand gun strikes, with the end of the arm L, the inclined plane B³ on the left, the corresponding sliding bar or bolt N is disengaged from the notch j¹ (Fig. 9); at the same time the sliding bar of the gun on the right due to the rotary movement imparted by the shaft K to the corresponding lever L—M, engages in the corresponding notch.

The gun on the left has then completed its movement of recoil while the gun on the right has completed its movement of running out. As soon as the gun on the right recoils, a rotary movement, in the same direction as before, is imparted to the shaft I, owing to the engagement of the groove I² with the catch j of the gun on the right, which catch is then fixed. At the end of the recoil of the gun on the right, the arm L of

the corresponding lever L—M climbs up the rear incline B³, which causes the corresponding sliding bar N to be released, at the same time as the sliding bar N of the gun on the left engages. A substantially continuous movement of rotation of the shaft I is thus produced, and, consequently, through the transmission H—G the continuous rotation of the shaft F of the fans.

Having now particularly described and ascertained the nature of my said invention and in what manner the same is to be performed, I declare that what I claim is:

1. A rapid firing gun recoiling in a cradle and characterized by the feature that the barrel comprises, for its guiding in the cradle, a sleeve, enclosing without clearance longitudinal ribs, projecting externally upon the front part of the barrel, the said sleeve being in turn externally provided with vertically projecting ribs, fitting without any lateral or horizontal clearance, but with a certain amount of vertical clearance, in corresponding grooves, and horizontal ribs fitting without any vertical clearance, but with horizontal clearance in other grooves in the said cradle, the said first mentioned ribs being pierced by orifices to allow the circulation of air or any other cooling fluid forced into one of the chambers formed between two adjoining ribs and the wall of the covering sleeve, the delivery being made through a pipe opening into the cradle.

2. A form of construction of the rapid firing gun as claimed in claim 1, wherein the cooling ribs are formed upon a hoop made of a metal which is a good conductor of heat, such as aluminium or an aluminium alloy.

3. A device of the class described comprising a cradle provided with horizontal and vertical grooves, a sleeve having ribs slidably engaging said grooves, the vertical ribs having vertical clearance and the horizontal ribs having horizontal clearance in said grooves, a gun secured to said sleeve, a hoop surrounding said gun and provided with radially extending cooling members having engagement with said sleeve, and means for admitting the cooling medium to the spaces formed between said ribs.

4. Ordnance apparatus comprising a cradle, a sleeve provided with horizontal and vertical ribs slidably mounted in said cradle, a gun rigidly connected to said sleeve, a cooling hoop disposed between said gun and sleeve, said hoop being provided with a plurality of radially extending and apertured cooling members having engagement with the sleeve, and means for supplying a cooling medium to the spaces between the hoop and sleeve for cooling said gun.

5. Ordnance apparatus comprising a gun, a hoop provided with radial ribs surrounding said gun, a sleeve surrounding said ribs

in engagement therewith and having horizontally and vertically disposed guide members and a cradle provided with grooves slidably engaged by said members, the horizontal members being adapted to prevent lifting or dropping of the gun and the vertical members being adapted to prevent transverse displacement of the gun.

6. A device of the class described comprising a gun, a hoop provided with radially extending ribs surrounding the gun, said hoop being formed out of metal which is a good conductor of heat, such as aluminum, a sleeve surrounding said ribs and having engagement with the extremities thereof, a cradle surrounding said sleeve, means carried by said sleeve for guiding the gun in its recoil in said cradle, and a port in the cradle for admitting a cooling medium between the hoop and sleeve.

7. In combination with a pair of alternating recoiling gun barrels, rotary means for supplying a cooling medium to said barrels and means utilizing the recoil energy of the barrels for actuating said rotary means.

8. Ordnance apparatus comprising, in combination, conjugated gun barrels, a slide for said barrels, means for employing the

energy of recoil of one barrel for running out the other barrel, rotary means for positively supplying a cooling medium to said barrels, and means energized by the recoil of said barrels for actuating said rotary means.

9. Ordnance apparatus comprising, in combination, conjugated gun barrels, a slide for said barrels, means for employing the energy of recoil of one barrel for running out the other barrel, rotary means including a fan for supplying a cooling medium to said guns, and means utilizing the recoil energy of the guns for rotating said fan.

10. A device of the class described comprising, in combination with a cradle, a pair of guns supported thereby, and means for employing the energy of recoil to one of said guns for running out the other of said guns, a hoop surrounding each of said guns, a sleeve interposed between each of said hoops and said cradle, a fan for each of the guns, and means actuated by the recoil of said guns for rotating said fans whereby a cooling medium is supplied to the guns.

In testimony whereof I have signed this specification.

NICOLAS EMILIEN METHLIN.
